UNITED STATES PATENT OFFICE.

EDGAR CHARLES THRUSS, OF WALTON-UPON-THAMES, ENGLAND.

TURBINE.

SPECIFICATION forming part of Letters Patent No. 699,636, dated May 6, 1902.

Application filed January 11, 1902. Serial No. 89,316. (No model.)

To all whom it may concern:

Be it known that I, EDGAR CHARLES THRUSS, civil engineer, a subject of the King of Great Britain and Ireland, residing at Southdene, 5 Ashley Park road, Walton-upon-Thames, in the county of Surrey, England, have invented certain new and useful Improvements in Turbines; and I do hereby declare the following to be a full, clear, and exact description of the 10 invention, such as will enable others skilled in the art to which it appertains to make and use the same.

In turbines as hitherto constructed the motive power is generally obtained by the reaction of the fluid issuing from the rotating part of the machine or by the impact of jets or currents directed against moving blades, vanes, or buckets, one of the main objects in view being to discharge the fluid from the 20 turbine at as low a velocity as possible. To accomplish this result, it is often necessary to work the machines at very high speeds, and this involves losses of power by friction of the fluid medium over fixed guide-blades or 25 against other fixed surfaces, or by friction of the rotating part against the fluid surrounding it, or losses of power by the rotating part acting as a centrifugal pump in the surrounding fluid, and also by the necessary speed-re- 30 duction gear connecting the turbine to the machinery which it serves to operate.

My present invention relates more particularly to turbines operated by gases under pressure, such as steam or compressed air; but it 35 is also applicable to turbines driven by water, and it differs from the usual types of turbines in that the object of my construction is to eliminate the element of impact and to derive the moving force from the friction of the 40 fluid medium on the surfaces of two or more flat parallel rotatable disks and not by its reaction on the rotating parts or by impact against moving blades or vanes or buckets.

With a turbine made in accordance with my 45 invention the highest efficiency is obtained when the speed of the disks is only a small fraction (one-third or even less) of the speed of the fluid passing through the annular spaces between the disks, and consequently the turbine 50 can be efficiently worked at more moderate speeds than can turbines as hitherto made.

One way of constructing the machine is by mounting two or more flat circular disks upon a rotatable shaft with intervening disks of 55 smaller diameter to separate the main disks, so as to leave narrow annular spaces between the main disks. The rotating shaft and disks are inclosed in a casing having, preferably, very small clearance-spaces and provided with 60 an inlet orifice or orifices for directing the fluid medium into the annular space or spaces between the disks and an outlet or outlets for the fluid medium arranged tangentially to the circumference of the disks in the manner com- 65 monly adopted for the discharge-outlets of centrifugal fans. If the fluid medium be a liquid, the inlet therefor is directed nearly tangentially to the periphery of the disks; but if the fluid medium be gas the direction of the inlet 70 therefor may be inclined at a greater angle to the tangent. The fluid thus enters the turbine at a high velocity and flows between the disks, driving them around by the force of its friction thereon, and the speed of move- 75 ment of the disks is considerably less than the velocity of the fluid; but as the fluid ad- vances the friction tends to reduce its velocity, while imparting power to the rotating disks and shaft. Another way of construct- 80 ing the machine is by mounting flat annular disks and separating-rings on a drum carried by a rotatable shaft. The turbine may be adapted to the compound or multiple effect principle by passing the fluid first through 85 one set of disks and afterward through an- other set or sets of disks situated in suc- cessive compartments of the inclosing case.

I will now describe, with reference to the accompanying drawings, manners in which 90 my invention can be carried into effect.

Figures 1 and 2 represent in sectional elevations at right angles to each other a single-jet non-reversible machine, more especially suited for small-size turbines to be driven by 95 steam. Fig. 3 is a transverse vertical section of a non-reversible turbine with the set of disks driven by two jets. Figs. 4 and 5 are sections at right angles to each other of a non-reversible turbine with the set of disks 100 driven by three jets. Fig. 6 shows in vertical section a reversible turbine with two jets, one for driving in one direction and the other for driving in the other direction. Fig.

7 shows in vertical section a reversible turbine with two jets for driving in each direction. Fig. 8 is a vertical section of a duplex machine in one case. Fig. 9 is a vertical section of a compound reversible turbine with two jets, one for driving in one direction and the other for driving in the other direction. Fig. 10 is a vertical section of a compound reversible turbine with three sets of disks in one case. Fig. 11 is a section of a portion of the disks and other parts drawn to a larger scale, showing a method of arranging the disks and of regulating the inlet-orifice. Fig. 12 is a section showing how the flat disks for large machines may be built up.

In all the figures corresponding parts are marked with the same letters of reference.

Referring first to Figs. 1 and 2, B is the fluid-inlet nozzle, fixed in the encircling ring 20 of the turbine-case C and furnished with a fluid-supply cock at A. D D are the disks upon which the fluid acts by friction, as aforesaid, and the spacing-disks or distance-pieces are marked E. It is impossible to indicate 25 the true thickness of the disks D and E in proportion to the other parts on a small-scale drawing, and therefore in Fig. 2 the lines D diagrammatically represent a number of very thin disks and the cross-hatched part represents 30 the parts of these disks separated by another set of disks or plates E. F is the shaft carrying the disks, and H H are rivets or bolts holding the disks D and E together by binding them tightly between the stiffening 35 end disks N N, secured to the shaft F. The main bearings of the shaft are marked L L. M M are the sides of the turbine-case, and K K are fluid-tight rings riding on the shaft F and turning inside the covers to prevent 40 leakage of the fluid medium. G is the exhaust or outlet for the fluid medium, which travels from the nozzle B, as indicated by the arrows and diverging dotted lines.

The double-jet non-reversible machine 45 (shown in Fig. 3) is suitable for driving dynamos, and so, also, is the non-reversible machine driven by three jets. (Shown in Figs. 4 and 5.) In this latter arrangement the rotating parts are shown as being secured to a 50 drum R, mounted on the shaft F, the two sets of disks being flat rings carried on the drum, with the stiffeners secured by rivets or bolts H H.

Fig. 6 illustrates a reversible machine with 55 a single jet for driving in each direction, the jet B and outlet G being for driving in one direction and the jet B' and outlet G' being for driving in the other direction.

Fig. 7 represents a reversible turbine having 60 two jets B B for driving in one direction and two other jets B' B' for driving in the other direction. The outlets are marked G G.

Fig. 8 shows a duplex arrangement of the 65 turbine having a single case C² with bearings for two shafts F F, each carrying a set of disks D D, these disks having no projec-

tions upon them, but overlapping in the path of the jet, leaving small spaces between the adjacent disks through which the fluid medium passes.

Fig. 9 is a compound reversible turbine operated by a single jet B or B' in either direction. The respective outlets are marked G G'.

Fig. 10 is a compound reversible machine 75 with three shafts, each with a set of disks, all inclosed in a single case C³ with three compartments, the central sets of disks being operated by two jets (B B or B' B') and the other two being operated each by one of these 80 jets.

Fig. 11 shows, drawn to an enlarged scale, the relative arrangement of the disks D and the disks or plates E, and also shows circular projections P pressed outward from the 85 disks D for abutting against adjacent disks to preserve the spacing of the disks D. These projections P are also shown in Fig. 1.

For large machines the disks or rings D and E may be built up in segments or sections 90 from several plates and be joined together by rivets passed through their abutting inclined edges, the heads Q of the rivets also acting as distance-pieces to preserve the correct spacing of the disks.

The speed of the said turbines may be regulated by manipulating the stop-cock on the fluid-supply pipe or by a throttle-valve governor regulating the pressure of the fluid supplied to the jets as commonly used in ordinary steam-engines or by a governor regulating the amount of opening of the supply-nozzle—as, for instance, by operating a slide to cut off the supply of fluid from some of the annular spaces between the disks D, as indicated by the slide O in Fig. 11.

I have shown a stop-cock on the inlet only in Fig. 1; but it is to be understood that the jets in the other figures may be similarly provided. Where I use more than one jet, these 110 jets may be controlled in common.

I do not limit myself to the precise details, proportions, and arrangements illustrated in the drawings, as it will be obvious that they can be varied without departing from the nature of my invention. For example, I may use a group of jets in place of each one shown, and any other suitable means of maintaining the disks in proper relative position may be used. I may connect the exhaust or exhausts 120 to a condenser when using steam as the fluid medium.

I claim—

1. A turbine comprising a shaft, a number of flat circular disks spaced apart on the shaft 125 and means for forcing a liquid in a straight line between the disks, whereby said disks and shafts are caused to revolve by the friction of the liquid on the sides of the disks, substantially as described.

2. A turbine having a casing, a shaft carrying flat disks spaced apart, means for pass-

ing a fluid through the spaces thus formed to rotate the disks by friction, and an inlet and an outlet both in the circumference of the casing, as described.

- 5 3. A turbine having a shaft carrying flat disks, spaced apart, an inlet for the motive fluid to rotate the disks by friction and an outlet in line with said inlet and tangential to the disks, substantially as described.
- 10 4. A turbine comprising a shaft carrying disks with annular spaces between them in combination with an inclosing casing provided with a fluid-inlet and an opposite outlet, in line with the inlet, whereby the fluid
- 15 passes in contact with the disks in a straight

line through the annular spaces between the disks to the outlet, substantially as described.

5. A turbine comprising a number of shafts, disks on said shafts, said disks being spaced apart, a casing for the shafts and disks and an inlet and an outlet in the casing placed in a line with each other and crossing the disks of more than one shaft, substantially as and for the purpose described.

In testimony whereof I affix my signature 25
in the presence of two witnesses.

EDGAR CHARLES THRUPP.
